UNITED STATES PATENT OFFICE.

BENJAMIN L. PARKINSON, OF LONDON, ONTARIO, CANADA, ASSIGNOR TO LONDON FREE PRESS PRINTING COMPANY LIMITED, OF LONDON, CANADA.

ASSEMBLING-ELEVATOR FOR LINOTYPE-MACHINES.

No. 872,967.

Specification of Letters Patent.

Patented Dec. 3, 1907.

Application filed May 13, 1907. Serial No. 373,498.

To all whom it may concern:

Be it known that I, BENJAMIN L. PARKINSON, a subject of the King of Great Britain, and a resident of the city of London, in the 5 county of Middlesex, in the Province of Ontario, Canada, have invented a new and useful Improvement on the Assembling-Elevator of Linotype-Machines, of which the following is a specification.

- 10 This invention relates to that portion of a linotype machine, where the matrices are assembled; and particularly to that class of a machine in which two-letter matrices are used.
- 15 The two-letter matrix just referred to is one that has two letters upon its face, one at a higher elevation than the other; the upper letter of which is usually Roman and the lower one Italic or black faced.
- 20 In use at present there are two classes of assembling elevators in linotype machines, in one of said classes the duplex rail has a longitudinal movement but no lateral or forward movement, and in the other class the duplex rail is formed in two sections, each of 25 which sections has an independent lateral or forward movement but no longitudinal movement.

In those machines in which the duplex rail 30 has a longitudinal movement but no lateral or forward movement, the inner edge of the duplex rail extends over on the lower front lug of the matrix, and when said duplex rail extends over on said lug of said matrix as described, it is not only inconvenient, but difficult to lift out a matrix to make a correction or for any other purpose, when assembling matrices to cast a line of Roman letters. Again in those classes of machines in which 35 the duplex rail has a lateral or forward but no longitudinal movement, the duplex rail is formed in two separate and independent sections, each of which is adjusted laterally or forwardly independent of one another. When 40 so-constructed and having only the lateral or forward movement, the disadvantage is, that when wishing to assemble a line of matrices to cast a line composed of both Roman and Italic or black faced letters, it is necessary for 45 the operator to grasp and hold up with his hand, the matrices from which the Italic or black faced letters are to be cast that extend over on the first section of the duplex rail, when it is required to fill out the line with 50 matrices from which to cast Roman letters.

This improvement consists in so constructing the assembling elevator, the duplex rail, and the line delivery channel, that said duplex rail may be adjusted laterally, to clear the lower front lug of the matrices when assembling a line of matrices to cast a line of Roman letters, and at the same time permit the duplex rail to be adjusted longitudinally in such a manner that it will be unnecessary for the operator to grasp or hold up with his hand any matrices when assembling a line of matrices to cast a line composed of both Roman and Italic or black faced letters, and further in such a manner that under all conditions or circumstances it will be unnecessary for the operator to grasp or hold up any matrices with his hand. All of which will be hereinafter more particularly described and claimed with reference to the accompanying drawings forming part of this specification, 75 wherein:—

Figure 1 is a front elevation of an assembling elevator, the duplex rail, and the line delivery channel, embodying my invention. In this view the assembling elevator is shown 80 in its elevated position by dotted lines. Fig. 2 is an enlarged detail perspective view of the inner face of the front portion of the line delivery channel. Fig. 3 is a plan view of the duplex rail and the front portion of 85 the assembling elevator. In this view the duplex rail is shown adjusted to receive the Italic or black faced letters. Fig. 4 is another view of same, showing the duplex rail adjusted longitudinally as well as laterally, to clear the lower front lugs of the matrices when assembling the latter to cast Roman letters. Fig. 5 is an enlarged detail front view of the duplex rail. Fig. 6 is an 90 enlarged detail front view of the upper portion of the assembling elevator, partly cut away to illustrate the springs and sockets therein more clearly. Fig. 7 is an enlarged detail end view of the upper portion of the assembling elevator, showing the matrices 100 in position when assembling to cast Italic or black faced letters. Fig. 8 is another view of same showing the matrices in position when assembling to cast Roman letters.

In the accompanying drawings:—The numeral 21 designates the assembling elevator, 105 22 the duplex rail supported on the upper face of the front portion of said assembling elevator, and 23 an outward and forward extension from said duplex rail, which is 110

grasped by the hand to facilitate its operation.

24 designates sockets formed in the upper face of the assembling elevator 21, and under 5 the duplex rail 22, and 25 designate coil springs which are fitted to and inserted in said sockets 24.

26 designates the duplex rail cap, which is held in place over the duplex rail 22 by 10 screws, *a*, secured in sockets, *b*, in the upper face of the assembling elevator 21 to prevent the vertical movement of said duplex rail.

27 designate L-shaped slots or openings formed in the duplex rail 22, and 28 pins 15 which are rigidly secured to the upper face of the front portion of the assembling elevator 21, and so arranged that when the duplex rail 22 is properly placed on said assembling elevator, said pins 28 will extend upwards into said L-shaped slots 27.

29 designate elongated narrow flanges formed on the inner side of and extending across the adjacent faces of the front and rear portions of the assembling elevator 21, 25 for the purpose which will be hereinafter set forth.

30 designates a gate which is pivotally mounted on a rod 31, supported in the front portion of said assembling elevator 21.

30 32 designates a two letter matrix provided on its opposite edges with the upper and lower lugs 33 and 34 respectively.

35 designates the line delivery channel, on the interior edge, of the front portion of 35 which adjacent to the front portion of the assembling elevator, 21, a recess, *c*, is formed, to permit the lateral and vertical movement of said duplex rail when the latter is carried vertically by the assembling elevator 21.

40 The purpose of the duplex rail in a machine of the class described is to hold the matrices so that those from which the lower or Italic or black faced letters are to be cast, will be in line with those from which the upper or Roman letters are to be cast.

45 The assembling elevator is that portion of the machine where the matrices are assembled.

The line delivery channel is that portion of 50 the machine into which the matrices pass from the assembling elevator.

The distance between the upper face of the flanges 29 and the top of the duplex rail 22, is equal to the distance between the bottom of the lower letter and the bottom of the upper letter on the matrix.

55 This being the case the operation is as follows:—When the line to be cast is from the upper or Roman letter, the duplex rail is 60 adjusted to the position shown in Figs. 4 and 8. When in this position the matrices are assembled and rest on the flanges 29. When the line to be cast is from the lower or Italic or black faced letter, the duplex rail is 65 adjusted to the positions shown in Figs. 3

and 7. When in this position the matrices are assembled and rest on the duplex rail, so that the Italic or black faced letter, which is the lower one on the matrix will be at the same elevation as the upper or Roman letter of the matrix. When said duplex rail 22 is in the position shown in Fig. 3, its end is flush with and just clear of the line delivery channel 35, and its inner side edge, *n*, extends inwards beyond the inner face of the front portion of the assembling elevator 21, as shown in Figs. 3 and 7. When in this position and the line to be cast is from the upper or Roman letter, *d*, on the matrix 32, the duplex rail 22 is adjusted to the position shown in Figs. 4 and 8, and when so adjusted the inner edge of said duplex rail 22 is flush with the inner side of the front portion of the assembling elevator 21, this permits the matrices to be delivered on the flanges 29, as shown in Fig. 8. And when adjusting said duplex rail 22, from the position shown in Figs. 3 and 7 to the position shown in Figs. 4 and 8, said duplex rail is first adjusted longitudinally until the portions of said duplex rail at the opposite ends of said longitudinal slots 27 abut against said pins 28, these pins 28 and slots 27 therefore regulate the longitudinal movement of said duplex rail, and when so adjusted the pins 28 will be in line with the lateral portion of said L-shaped slots 27; said duplex rail 22 is then adjusted laterally or forward or toward the operator until the portions of the duplex rail at the inner ends of the lateral portions of the L-shaped slots 27 abut against said pins 28, as shown in Fig. 4, these pins 28 and slots 27 again regulating the movement of said duplex rail 22 laterally, and prevents all possibility of any excessive or irregular movement of said duplex rail 22. But after adjusting said duplex rail, longitudinally, its end portion extends over on the line delivery channel 35 as shown in Fig. 1, and when in this position, in order to permit said end of said duplex rail to be adjusted, laterally or forward, the space between the inner adjacent faces of the line delivery channel must be increased, or the inner edge of the front side portion thereof adjacent to the front portion 100 of the assembling elevator must be cut away as shown at, *c*, in Fig. 2, to permit the end of said duplex rail 22 that extends over on said line delivery channel 35 to be adjusted laterally or forward, and at the same time permit the assembling elevator to be raised and lowered when said duplex rail is in this position. When said duplex rail 22 is in the position shown in Figs. 4 and 8, and the line to be cast is from the lower or Italic or black 105 faced letter on the matrices, the reverse operation to that just described takes place; when the reverse movement takes place, the lateral movement of the duplex rail 22 inwards is regulated by the sides of the elongated

gated slots 27, and the longitudinal movement by the portions of the duplex rail 22 engaging with the pin 28 as shown in Fig. 3. In this position the matrices 32 are delivered 5 on the overhanging edge, *n*, of the duplex rail 22 as shown in Fig. 7; and the distance from the upper face of the flanges 29 to the upper face of the duplex rail 22, being the same as the distance from the bottom of the 10 upper or Roman letter, *d*, to the bottom of the lower or Italic or black faced letter, *e*;— the Italic or black faced letters, *e*, to be cast from; when in this position will be at the same elevation as that at which the upper or 15 Roman letters were when assembled to be cast from. Consequently when assembling the matrices to cast a line of Roman letters and a word near but not quite at the end of the line is required in Italic, the duplex rail 20 which is in the position shown in Figs. 4 and 8, when the matrices for casting upper or Roman letters, *d*, are assembled, may be readily, easily, and instantly, by grasping the extension 23, adjusted to the position 25 shown in Figs. 3 and 7, when the Italic or black faced letters, *e*, when delivered on the duplex rail, will be in line with the Roman letters, *d*, to be cast from, and if the word, sentence or paragraph whatever it may be, 30 did not quite fill out that line or any other line if the insertion in Italic was extensive; by adjusting the duplex rail longitudinally only, the duplex rail although projecting over the inner edge of the line delivery chan- 35 nel, there would be a space between the duplex rail 22 and the end of the assembling elevator, shown at, *o*, in Fig. 1, which would permit the matrices to be delivered on the flanges 29, for the balance of the line. And 40 if the insertion in Italic hereinbefore referred to should be extensive it would not be necessary to make any change in the adjustment of the duplex rail 22 until the assembling of matrices to complete said insertion in Italic 45 was completed.

The purpose of the spring 25 is to prevent the accidental movement of the duplex rail, by the vibration of the machine when in operation.

50 As a result a simple, strong, durable and inexpensive improvement is provided which is perfect in efficiency when in practical use, and which avoids and completely prevents under any or all conditions or circumstances, 55 any possibility of the operator being required to grasp or hold up any matrices by hand.

I have found by experiment that the construction herein shown and described gives the best results, at the same time while I 60 prefer said construction, I do not wish to limit myself to the details thereof, as it may be modified in various ways, without departing from the spirit of my invention.

Having thus described my invention, I 65 claim:—

1. In a linotype machine, an assembling elevator for receiving the matrices in combination with a duplex rail adjustable longitudinally and laterally on the assembling elevator for supporting said matrices. 70

2. In a linotype machine, a duplex rail in combination with an assembling elevator and adapted to be adjusted longitudinally and laterally on the same, sockets formed in the upper front portion of said assembling elevator, and springs in said sockets adapted to resiliently engage with said duplex rail, substantially as shown and described and for the purpose specified. 75

3. In a linotype machine, a duplex rail in combination with an assembling elevator and adapted to be adjusted longitudinally and laterally on the same, and a line delivery channel in the inner edge of which adjacent to the assembling elevator, a recess is formed, 80 substantially as shown and described and for the purpose specified. 85

4. In a linotype machine, a duplex rail in combination with an assembling elevator and adapted to be adjusted longitudinally and laterally on the same, sockets formed in the upper front portion of said assembling elevator, springs in said sockets adapted to resiliently engage with said duplex rail, and a line delivery channel in the inner edge of 90 which adjacent to the assembling elevator, a recess is formed, substantially as shown and described and for the purpose specified. 95

5. In a linotype machine, a duplex rail in which angular shaped slots are formed, in combination with an assembling elevator provided with pins which are fitted to and inserted in said angular shaped slots, substantially as shown and described and for the purpose specified. 100

6. In a linotype machine, a duplex rail in which angular shaped slots are formed, in combination with an assembling elevator provided with pins which are fitted to and inserted in said shaped slots, sockets formed 110 in the upper front portion of said assembling elevator, and springs in said sockets adapted to resiliently engage with said duplex rail, substantially as shown and described and for the purpose specified. 115

7. In a linotype machine, a duplex rail in which angular shaped slots are formed, in combination with an assembling elevator provided with pins which are fitted to and inserted in said angular shaped slots, and a 120 line delivery channel in the inner edge of which adjacent to the assembling elevator, a recess is formed, substantially as shown and described and for the purpose specified.

8. In a linotype machine, a duplex rail in which angular shaped slots are formed, in combination with an assembling elevator provided with pins which are fitted to and inserted in said angular shaped slots, sockets 125 formed in the upper front portion of said 130

assembling elevator, springs in said sockets
adapted to resiliently engage with said du-
plex rail, and a line delivery channel in the
inner edge of which adjacent to the assem-
bling elevator, a recess is formed, substan-
tially as shown and described and for the pur-
pose specified.

In testimony whereof, I have signed in the
presence of the two undersigned witnesses.

BENJAMIN L. PARKINSON.
